US00D599648S

(12) **United States Design Patent**
Dubon

(10) **Patent No.:** **US D599,648 S**
(45) **Date of Patent:** **** Sep. 8, 2009**

(54) **HEAVY DUTY TELESCOPING SLIDE
HARDWARE**

(75) Inventor: **William Dubon**, Bloomingdale, IL (US)

(73) Assignee: **Pentair Electronic Packaging
Company**, Des Plaines, IL (US)

(**) Term: **14 Years**

(21) Appl. No.: **29/301,255**

(22) Filed: **Feb. 19, 2008**

Related U.S. Application Data

(63) Continuation of application No. 29/244,693, filed on Dec. 13, 2005, now Pat. No. Des. 562,117.

(51) **LOC (9) Cl.** **08-05**

(52) **U.S. Cl.** **D8/374**

(58) **Field of Classification Search** **D8/374;**
312/333, 334.44, 334.46

See application file for complete search history.
